DESIGN FOR A PHOTOGRAPHIC ENLARGING APPARATUS

Albert Drucker, Chicago, Ill., assignor to Burke & James, Inc., Chicago, Ill., a corporation of Illinois

Application October 2, 1940, Serial No. 95,559

Term of patent 14 years

To all whom it may concern:

Be it known that I, Albert Drucker, a citizen of the United States, residing at Chicago, in the county of Cook and State of Illinois, have invented a new, original, and ornamental Design for a Photographic Enlarging Apparatus, of which the following is a specification, reference being had to the accompanying drawing forming a part thereof.

The figure is a perspective view of a photographic enlarging apparatus, showing my new design.

I claim:

The ornamental design for a photographic enlarging apparatus, as shown.

ALBERT DRUCKER.
